UNITED STATES PATENT OFFICE.

GILBERT L. CROWELL, JR., OF ARLINGTON, NEW JERSEY, ASSIGNOR TO
DOMINICK & HAFF, OF NEW YORK, N. Y.

DESIGN FOR A SILVERSMITH'S STOCK.

SPECIFICATION forming part of Design No. 24,380, dated June 11, 1895.

Application filed May 11, 1895. Serial No. 549,020. Term of patent 7 years.

To all whom it may concern:

Be it known that I, GILBERT L. CROWELL, Jr., a citizen of the United States, residing at Arlington, in the county of Hudson and State 5 of New Jersey, have invented and produced a new and useful Design for Silversmiths' Stock and Similar Articles, of which the following is a full and complete specification, reference being had to the accompanying drawing, which illustrates the design.

The design consists of a strip or ribbon of silversmiths' stock showing a series of bunches of grapes and intervening grapevine tendrils and leaves, alternating with each other, in 15 connection with two running grape vines, as shown in the drawing, in which—

A represents the bunches of grapes.
B represents the grape-vine tendrils.
C represents the grape-vine leaves, and D
D represent the two running grape-vines. 20
The essential features of the design are those above indicated.

What is claimed as new is—
The design for silversmiths' stock and similar articles, substantially as shown and de- 25
scribed.
